PRONE BODY HOIST

Guy J. Hawkins, Milwaukee, Wis., assignor to
Hawkins Electro-Lift Co., Milwaukee, Wis., a
corporation of Wisconsin

Application May 1, 1950, Serial No. 159,271

5 Claims. (Cl. 27-28)

1

This invention relates to improvements in prone body hoists.

A general object of the invention is to provide a hoist for mortuary or hospital usage adaptable for the vertical shifting of prone and inert human bodies.

In mortuary establishments and in hospitals, it is frequently necessary to vertically shift an inert prone human body and it is highly desirable when a mechanical hoisting device is used for this purpose that it be susceptible of being so engaged with the body as to not disturb the position of the body or to bend or flex the body. With a body hoist for mortuary use, for instance, it is necessary to move an embalmed corpse from the embalming table to the casket and in shifting the prone inert body, it must be engaged by the hoisting mechanism in such a manner that the head of the corpse will not be disturbed and also so that the prone body will not be bent or flexed, as it is necessary that the make-up, dress, etc., be preserved in the prepared condition.

With the above in mind it is, therefore, a primary object of the present invention to provide a wheeled, prone body hoist of an open framework construction which may be manually pushed over a bed or embalming table to engage and elevate a prone inert human body and which may be subsequently wheeled to a different location to permit the lowering of the body, without disturbing it, into a casket, bed or support in a remote location.

A further object of the invention is to provide a prone body hoist which securely engages the body along several removed points and which furthermore firmly engages the body head, with the engaging members being operable jointly and simultaneous to vertically shift the body without disturbing its inclination or prone position, and which maintains the body head in a desired adjusted position.

A further object of the invention is to provide a prone body hoist in which the hoisting mechanism is electrically operated whereby one attendant can easily lift and move a prone inert human body.

A further object of the invention is to provide a hoist of the character described which, while useful for handling and lifting an unconfined inert human body, may also be used for vertically moving caskets, vaults, stretchers and other enclosures in or on which a prone human body may be disposed.

A further object of the invention is to provide a prone body hoist which is portable, which is of simple construction, which is easy to operate and

2

manipulate, and which is well adapted for the purposes described.

With the above and other objects in view the invention consists of the improved prone body hoist, and its parts and combinations as set forth in the claims, and all equivalents thereof.

In the accompanying drawings in which the same reference characters indicate the same parts in all of the views:

Fig. 1 is a side view of the improved prone body hoist showing it engaged with, for elevating purposes, a prone inert human body;

Fig. 2 is an end view of the hoist with a portion broken away and in section to show structural details;

Fig. 3 is a plan view of the hoist;

Fig. 4 is an enlarged fragmentary detail sectional view taken on line 4-4 of Fig. 2; and

Fig. 5 is an enlarged fragmentary detail sectional view taken on line 5-5 of Fig. 2.

Referring now more particularly to the drawings, it will appear that the improved body hoisting apparatus is embodied in an open portable, adjustable frame work which includes a pair of end standards 10 of inverted U-form and held in longitudinally spaced apart relation by horizontal frame members to be described. The lower extremities of the arms of the end standards 10 have swivellingly mounted thereon casters 11. All of the members constituting the open frame work, including the end standards and the connecting horizontal members are formed of tubular steel. The closed, reduced upper end portions of the pair of separated end standards are connected by laterally spaced apart top longitudinal frame members 12 which are of telescopic formation so as to be longitudinally adjustable and which are provided with registering apertures through which pins may be inserted for securing the telescopic members in their extended positions.

The opposite extremities of the top members 12 are reduced and are revolvably extended through bearing openings therefor in the top cross portions of the end standards 10. The reduced portions, at one end, are further extended and are formed with integral pinions 13. These pinions are adapted to mesh with worms 14 fast on a transverse driven end shaft 15 journaled in end bearing blocks 16 carried by an adjacent portion of the end standard 10. Said shaft 15 has also formed thereon a worm gear 17 meshing with and driven by a worm 18 fast on the outer end portion of the motor shaft of an electric motor 19 supported on a bracket carried by the framework, as shown.

It will thus be seen that the top longitudinal members 12 are adapted to be revolved. Along the lengths of the latter are series of apertures 20, 21 and 22 for the selective anchorage of pairs of spaced apart spools 23, 24 and 25. The parallel, laterally spaced apart top longitudinal members 12, therefore, carry the pairs of spools with the spools of each pair laterally spaced apart. The spools 23 have attached thereto the opposite upper ends of straps 26 whose lower ends carry a U-shaped leg harness 27. The upper ends of straps 28 are secured to the intermediate spools 24 and the lower ends of said straps 28 carry a U-shaped hip harness 29. The upper ends of straps 30 are secured to the spools 25 and the lower ends of said straps carry a U-shaped shoulder harness 31. It will be observed that the harnesses 27, 29 and 31 are normally preferably at elevations progressively graduated toward the head end of the apparatus with the result that the engaged body is supported in a prone position slightly downwardly inclined toward the foot end, as shown in Fig. 1, as this is the preferable position for disposing a prone body in a casket.

It should also be observed that the pinions and gears to drive the longitudinal members 12 on which the spools 23, 24 and 25 are mounted, are arranged to revolve said members 12 in opposite directions for the purpose of winding or unwinding the straps 26, 28 and 30 relative to their respective spools. The pin and aperture means for the anchorage of the spools on the longitudinal members 12 permits the adjustment of the spools on said members so as to properly locate the harnesses 27, 29 and 31 relative to the portions of the body to be supported.

It will be observed from Fig. 2 that one of the vertical arms of the end standard 10 at the head end of the apparatus revolvably houses a vertical screw 32 whose lower end is journaled in a block 33 in the lower end of said standard arm. The upper unthreaded portion of the screw 32 extends outwardly of the upper end of the standard arm and carries fast thereon a wormgear 34 meshing with a worm 35 on the end of the driven transverse shaft 15. Through this means, therefore, the vertical screw 32 is driven from the electric motor 19. A side wall portion of the tubular arm of the standard 10 which houses the screw 32 is formed on its inner side with a slotted opening 36 through which the bracket portion of a travelling nut 37 laterally extends, the traveling nut being in screw threaded engagement with the vertical screw 32. The free end portion of an arm 37' associated with the travelling nut is formed with a bored boss 38 which adjustably receives the shank portion 39 of an adjustable head cup 40. The latter is mounted on a horizontal sleeve 41 adjustably carried on the stem 39. The head cup is adapted to be adjustably positioned so as to engage and support the rear of the head of a prone human body 60, as shown in Fig. 1, and it permits the head to be turned in any desired position and to maintain the head in this position relative to the remainder of the engaged and supported body.

When the electric motor 19 is energized to cause its operation, through the shafts and gearing described, the transverse shaft 15 will be turned to revolve the upper longitudinal members 12 and thus turn the spools thereon to wind or unwind the straps 26, 28 and 30. Simultaneously, the vertical screw 32 will be driven to

cause the travelling nut 37 and the head cup 40 to be raised or lowered, according to the movement imparted to the harnesses, and at the same rate of speed so that as the portions of the body 60, engaged by the harnesses are moved, the body head supported by the cup 40 will be similarly moved.

The open framework, in addition to the top longitudinal members 12, which are driven, has the end standards 10 spacedly connected by telescopic longitudinal frame members 42 disposed below and outwardly of the members 12, and by bottom telescopic longitudinal members 43. While the members 42 are formed integral with the end standards 10, the bottom longitudinal connecting members 43 have their outer ends reduced and hook-shaped, as at 43', to engage in recesses 44 provided therefor in supporting rings 45 (see Fig. 5) which are clamped to lower portions of the vertical arms of the end standards 10. Also, the supporting rings 45 are adapted to be engaged by the hooked extremities 46 of transverse bottom bars 46. The longitudinal bottom bars 43 and the transverse bottom bars 46 are hookingly engaged with the members 45 so that they may be completely removed from the framework when desired to make the lower portion of the framework completely open so that it may be rolled over a table or bed, when desired, without obstruction.

In the use of the improved prone body hoist in a mortuary establishment, for instance, it may be desirable to move an embalmed human body from an embalming table to a casket at a separated location. The face of the body has had makeup applied thereto and the balance of the body is clothed and it is essential that the body be shifted without disheveling the clothing or causing any substantial movement of the body head which might disturb the makeup and hairdress. With the improved hoisting apparatus, through the temporary removal of the bottom bars 43 and 46, the open frame-work may be wheeled directly over the body on the embalming table. At this time, the head cup 40 on the supporting member 39 has been swivelled to an out-of-the-way position. The various harness members 27, 29 and 31, initially detached from their respective straps, are engaged under the leg, hip and shoulder portions of the body 60 and the head cup 40 is lowered and swung under the head of the human body. The straps 26, 28 and 30 having been lowered, are then engaged with their respective harnesses and if adjustments are desired the spools 23, 24 and 25 may, as previously noted, be shifted along their shafts 12.

After the prone body has been thus properly engaged the motor 19 may be started and it will be effective to simultaneously wind the various straps on their spools and to elevate the travelling nut 37 which carries the head cup 40. The various portions of the prone body are engaged by the means described, with said means being operated to elevate the human body slowly and evenly in a position of slight inclination and without disturbing or in any way flexing the body. When the body has been thus elevated above the embalming table the entire wheeled framework, carrying the body, may be wheeled over the casket whereupon the motor 19 is operated in a reverse direction to cause a lowering of the elements which carry the human body, whereby the body may be slowly and evenly de-

posed into the casket in a desired position without disturbing it.

While the operation of the prone body hoist has been described in detail in connection with a mortuary establishment, it is obvious that it may be used to advantage in a hospital for the purpose of removing a human body from a hospital bed or operating table and transporting it to another location. Additionally, the hoist is susceptible of use in connection with devices or containers in or on which the human body is disposed as a stretcher, casket, vault or the like. For the latter purposes the several harness members 27, 28 and 31 may be slung around the container to be moved and then engaged with their respective straps and upon operation of the motor the stretcher, casket or the like can be elevated or lowered and, while being carried, the entire assemblage may be wheeled to any desired location. In the use of the improved hoist it is obvious that the same requires the attention of but a single operator.

In the drawings, the open framework is shown in its extended, operative condition. If it is desired to collapse the framework for storage or handling, it is merely necessary to remove the pins which join the complementary sections of the longitudinal frame members 12, 42 and 43. Then, through the telescoping of these frame members, one of the end standards may be pushed toward its companion end standard to thus temporarily shorten the assemblage for more convenient storage, it being understood that the anchorages for the spools on the upper frame members are also removed to permit the spools to slide.

From the foregoing description it will be evident that the improved prone body hoist is of simple and novel construction, is easy to operate, provides for the moving of a prone human body without disturbing the latter, and is well adapted for the purposes set forth.

What is claimed as the invention is:

1. A hoist for a prone human body, comprising a portable, open framework, an elevator, means vertically movably mounting said elevator in one end portion of said framework, a head support angularly adjustably carried by said elevator, laterally spaced shafts revolvably mounted longitudinally of the upper portion of said framework, a plurality of body supporting harness members spacedly depended from portions of said shafts and adapted to be wound and unwound relative thereto, motion transmitting means operatively connected with said shafts and with said elevator, and power means engaging said motion transmitting means for simultaneously moving said elevator and revolving said shafts in synchrony.

2. A hoist for a prone human body, comprising a portable, open framework, an elevator, means vertically movably mounting said elevator in one end portion of said framework, a head support angularly adjustably carried by said elevator, laterally spaced shafts revolvably mounted longitudinally of the upper portion of said framework, a plurality of body supporting harness members spacedly depended from portions of said shafts and adapted to be wound and unwound relative thereto, a power shaft in driving engagement with the first-mentioned shafts and said

elevator, and electric motor means for driving said power shaft.

3. A prone body hoist, comprising an open framework including top longitudinal revoluble shafts and vertical corner posts, pairs of spaced spools carried by said shafts to turn therewith, body engaging harness members depended from said spools to be wound and unwound relative thereto, a head support vertically movably mounted on one of said corner posts, and means extending to both said head support and said revoluble shafts for operating the head support and spools simultaneously and in synchrony.

4. A mechanical hoist for a prone human body, comprising vertical end standards, telescopic top longitudinal frame members spacedly connecting said end standards, a pair of said longitudinal frame members being journaled in said end standards for rotation, bottom longitudinal frame members detachably associated with said end standards, said end standards and all of said longitudinal frame members constituting an open framework, pairs of spaced spools adjustably mounted on said rotatable longitudinal frame members to turn therewith, body engaging flexible slings depended from said spools to be wound and unwound relative thereto, an elevator, means vertically movably mounting said elevator in one of said end standards, a head support angularly adjustably carried by said elevator, motion transmitting means operatively connected with said rotatable longitudinal frame members and with said elevator; and means engaging said motion transmitting means for operating the elevator and said rotatable longitudinal frame members simultaneously.

5. A mechanical hoist for a prone human body, comprising vertical end standards, telescopic top longitudinal frame members spacedly connecting said end standards, a pair of said longitudinal frame members being journaled in said end standards for rotation, bottom longitudinal frame members detachably associated with said end standards, said end standards and all of said longitudinal frame members constituting an open framework, pairs of spaced spools adjustably mounted on spaced-apart portions of said rotatable longitudinal frame members to turn therewith and movable with said longitudinal frame members when the latter are telescopically adjusted, body engaging flexible slings depended from said spools to be wound and unwound relative thereto, and power means for revolving said rotatable longitudinal frame members in either direction.
